(57) **CLAIM**

I claim the ornamental design for a portable cleaning station basin, as shown and described.

DESCRIPTION

FIG. 1 is a top, front, right side perspective view of my new design for a portable cleaning station basin;

FIG. 2 is a perspective view from beneath the back left side thereof;

FIG. 3 is a perspective view from above the front left side thereof;

FIG. 4 is a top plan view thereof;

FIG. 5 is a bottom plan view thereof;

FIG. 6 is a right side view thereof;

FIG. 7 is a left side view thereof;

FIG. 8 is front view thereof; and,

FIG. 9 is a back view thereof.

The broken lines depict portions of the portable cleaning station basin that form no part of the claimed design.
